UNITED STATES PATENT OFFICE.

JESSE G. VINCENT, OF DETROIT, MICHIGAN, ASSIGNEE TO PACKARD MOTOR CAR COMPANY, OF DETROIT, MICHIGAN, A CORPORATION OF MICHIGAN.

HYDROCARBON MOTOR.

Application filed December 23, 1920. Serial No. 432,823.

This invention relates to hydrocarbon motors and particularly to the construction of the cylinder block and the means for conveying the mixture from the carburetor to the motor cylinders, as well as for heating the mixture.

One of the objects of the present invention is to provide a novel and particularly advantageous system of intake passages for the mixture of a hydrocarbon motor.

Another object of the invention is to provide both exhaust heating means and combustion heating means, of a novel character, for raising the temperature of the mixture of a hydrocarbon motor.

Another object of the invention is to provide a hydrocarbon motor with aligned intake passages fed by separate horizontal passages which will prevent surging of the mixture from one end of the motor towards the other.

Another object of the invention is to provide an intake elbow of novel form with a combustion heater discharging thereinto and receiving its mixture from the vertical passage of the elbow and below the throttle valve thereof.

Other objects of the invention will appear from the following description taken in connection with the drawings, which form a part of this specification, and in which:

Fig. 1 is a side elevation of a hydrocarbon motor embodying this invention;

Fig. 2 is a vertical transverse section through the motor shown in Fig. 1 and substantially on the line 2—2 of Fig. 1 as well as on the line 2—2 of Fig. 4;

Fig. 3 is a slightly enlarged vertical section on the line 3—3 of Fig. 2; and

Fig. 4 is a horizontal section substantially on the line 4—4 of Fig. 2.

Referring to the drawings, 10 represents a cylinder block of usual construction in so far as the cylinders 11 and other conventional parts are concerned. A detachable head 12, a spark plug 13, and an intake valve 14 with valve springs 15, are shown particularly in Fig. 2.

This cylinder block is preferably formed with six cylinders and the motor is of the usual four-cycle type with the cylinders firing in the order of 1—5—3—6—2—4 or so that the explosions jump back and forth from one of the first three cylinders to one of the lat-

ter three and then to the first three, etc. 55 through the complete cycle.

With such firing order, in a six cylinder motor it is found that if the six intake ports are connected by a single intake passage extending longitudinally of the block, there 60 will be more or less surging of the mixture from one end of the passage towards the other because of the opening of an intake valve in the front half of the block followed by the opening of an intake valve in the rear 65 half of the block and then the opening of an intake valve in the front half of the block again, and so on. The present invention prevents this surging of the mixture by forming two aligned intake passages in the cylinder 70 block, which passages connect with the various intake ports of the cylinders and have their inlet ends arranged adjacent to each other near the middle of the block. The mixture is then fed to the inlet ends of these 75 intake passages by two elongated horizontal passages so that the mixture can not get from one of the cylinder block intake passages to the other without going all the way back through one of the horizontal passages and then forward through the other one. This 80 of course is practically impossible and the surging is thereby prevented.

The two aligned intake passages of the cylinder block are indicated at 16 in Figs. 2 85 and 4, and it will be seen that their inlet ends 17 are arranged adjacent to each other at the middle of the cylinder block. These passages 16 communicate with the inlet ports 18 by inclined passages 19, one of which is 90 shown in Fig. 2.

Each of the intake passages 16 is rectangular in cross section as are also their inlet ends 17, and adjacent the ends 17 the passage makes a right angle bend in a substantially 95 horizontal plane. The flat sides of the passage merge into the flat top and bottom walls by fillets or circular arcs of short radius, and these flat sides make sharp bends with similar arcs of short radius, whereby the mixture 100 from the carburetor travels through the passage 20 and end 17 and strikes the vertical flat surface at the bend, and that surface being normal to the center line of the passage anterior to the bend, the mixture continues in 105 its horizontal path to the valved intake ports of the engine.

Communicating with the inlet ends 17 of

these intake passages are two horizontal passages indicated generally at 20 and the passages 20 are not brought together until the end of a partition is reached at 21.

5 A part of each of the horizontal passages 20 is formed transversely in an integral portion 22 of an exhaust pipe or manifold 23 which extends alongside the cylinder block and is secured to it by branches 24 and nuts 25. The 10 branches of this exhaust manifold communicate with the exhaust ports of the motor cylinders.

The outer part of each of the horizontal passages 20 is formed in an elbow 26, which is 15 attached to the exhaust manifold 23 as by bolts 27. Thus the elbow 26 may be said to have two horizontal passages 28 forming the outer ends of the horizontal passage 20.

The vertical branch of the elbow 26 is 20 formed with a single passage 29 in which there is a throttle valve 30 for controlling the quantity of mixture passing to the motor. To the lower end of this vertical branch of the elbow is secured a carburetor 31 having a 25 Venturi tube 32 and a fuel nozzle 33 cooperating therewith. The carburetor also comprises a float chamber 34, a main air intake 35, and an auxiliary air intake 36. Any other conventional form of carburetor may be used 30 in lieu of the one illustrated.

Formed separately or as an integral part of the elbow 26 is a combustion heater device 37. As shown, it comprises a combustion chamber 38, a jacket 39 surrounding a part of the elbow 35 26, a spark plug 40 for firing the mixture, an inlet port 41, and a glass window 42 for observing the burning of the mixture in the chamber 38. The outlet for the burned mixture from the combustion heater is indicated 40 at 43 at the juncture between the vertical passage 29 of the elbow and the horizontal passages 28 thereof. It is located at the lowest part of the jacket 39 whereby any liquid fuel that may condense in the chamber will be discharged immediately through this port 43 and not collect in the chamber. Thus the mixture being drawn up through the elbow meets the hot burnt gases drawn in through the port 43 and is materially heated thereby. The mixture 45 is also heated indirectly through the walls of the jacket 39 as it passes to the motor.

Moreover, after the motor gets into operation the mixture is further heated by reason of the proximity of the horizontal passages 50 20 to the exhaust manifold 23.

In order that the combustion heater may operate in the most desirable way, which is at its maximum with the throttle closed and at its minimum with the throttle open, the mixture withdrawing means for the combustion heater is arranged below the throttle valve 30, and as shown, this mixture withdrawing means comprises a conduit 44 having one or more inlet ports 45, in the stem of the throttle valve. The ports 45 are so arranged that

they open on the under side of the throttle when the latter is in closed position as shown in Fig. 2. In Fig. 3 it will be seen that the conduit extends to the outer end of the stem of the throttle valve and a pipe 46 leads from that point to the combustion heater. In Fig. 1 this pipe 46 is shown as extending upwardly to the inlet port 41 of the combustion heater 37.

By this arrangement of the throttle valve 75 in the vertical branch of the elbow 26, and the placing of the mixture withdrawing means within the throttle valve immediately above the carburetor, the division or partition between the horizontal passages 20 may extend all the way from the motor cylinder block to the turn in the elbow to thereby obtain the non-surge effect hereinabove described.

It will be understood that various forms of the invention other than those described above may be used without departing from the spirit or scope of the invention.

Having thus described my invention, what I claim and desire to secure by Letters Patent is:

1. In a hydrocarbon motor, the combination with a cylinder block having aligned intake passages with their inlet ends adjacent each other near the middle of the block, of an exhaust manifold connected to said cylinder block and having transverse intake passages formed therein and connected to the inlet ends of said intake passages, and a carburetor connected to said exhaust manifold 95 and communicating with said transverse passages.

2. In a hydrocarbon motor, the combination with a cylinder block having aligned intake passages with their inlet ends adjacent each other near the middle of the block, of an exhaust manifold connected to said cylinder block and having transverse intake passages formed therein and connected to the inlet ends of said intake passages, an intake elbow 105 connected to said exhaust manifold and having passages communicating with said transverse passages, and a carburetor connected to said elbow.

3. In a hydrocarbon motor, the combination with a cylinder block having aligned intake passages with their inlet ends adjacent each other near the middle of the block, of means forming elongated horizontal passages connecting respectively with the inlet ends 115 of said intake passages, means forming a vertical passage in communication at its upper end with the outer ends of both of said horizontal passages, a carburetor connected to supply mixture to said vertical passage, a combustion heater at the juncture of said vertical and horizontal passages, and means in said vertical passage for withdrawing 125 part of the mixture passing therethrough and feeding it to said combustion heater. 130

4. In a hydrocarbon motor, the combination with a cylinder block having intake passages, of an intake elbow having a vertical passage and two horizontal passages communicating therewith, means connecting said horizontal passages with the intake passages of the motor, a carburetor connected to the lower end of the vertical branch of said elbow, a combustion heater on said elbow and having its discharge opening in communication therewith, a throttle valve in the vertical passage of said elbow above said carburetor, and means adjacent said throttle valve and opening into the vertical passage below said throttle valve when the latter is in closed position, which said latter means is adapted to withdraw a part of the mixture passing through said elbow and feeding it to said combustion heater.
5. In a hydrocarbon motor, the combination with an intake elbow having vertical and horizontal passages, of a carburetor connected to the lower end of the vertical passage, a combustion heater having its outlet in communication with said elbow, a throttle valve in said vertical passage above said carburetor, said throttle valve having a conduit communicating with the vertical passage in the elbow below said throttle valve when the latter is in closed position, and means connecting said throttle conduit with said combustion heater for carrying mixture from the vertical passage of the elbow to said heater.
6. In a hydrocarbon motor, the combination with an intake elbow, of a combustion heater comprising a chamber forming a jacket on the outer part of the turn in said elbow, said chamber having an outlet port from its lowest part into the elbow.
7. In a hydrocarbon motor, the combination with the carburetor and the valved intake ports of the engine, of an intake conduit extending between the carburetor and the valved ports, a section of said conduit having a single passage of substantial size, said passage making a sharp right angle bend in a substantially horizontal plane and being rectangular in cross section with flat sides merging into flat top and bottom walls by fillets or circular arcs of short radius and with said flat sides making the sharp bend with similar arcs of short radius, whereby the mixture strikes a vertical flat surface at the bend normal to the center line of the passage anterior to the bend.

In testimony whereof I affix my signature.
JESSE G. VINCENT.
